UNITED STATES PATENT OFFICE.

THOMAS HASKINS, OF LASALLE, ILLINOIS.

MIXING AND WASHING MACHINE.

SPECIFICATION forming part of Letters Patent No. 736,389, dated August 18, 1903.

Application filed May 28, 1902. Serial No. 109,069. (No model.)

To all whom it may concern:

Be it known that I, THOMAS HASKINS, a citizen of the United States, residing at Lasalle, in the county of Lasalle and State of Illinois, have invented a new and useful Mixing and Washing Machine, of which the following is a specification.

This invention relates to certain improvements in machines for mixing cement, concrete, and other substances, and has for its principal object to provide an improved device which will rapidly and thoroughly mix cement with gravel, broken stone, and like material to form concrete for paving and other purposes.

A further object of the invention is to provide a machine of this class in which the quantity of cement supplied to the other material in the mixing-trough may be accurately regulated and evenly distributed.

A still further object of the invention is to so arrange and construct the device that the supply may be cut off at any time in order to avoid the mixing of more material than is necessary for the work intended.

A still further object of the invention is to provide a device of this class which may be readily moved from place to place and in which the mixed material may be discharged either directly at the place where it is to be used or into wheelbarrows for transportation.

A still further object of the invention is to so arrange and construct the machine as to provide for the washing of gravel, broken stones, and other granulated material.

With these and other objects in view the invention consists in the novel construction and arrangement of parts hereinafter described, illustrated in the accompanying drawings, and particularly pointed out in the appended claims.

In the drawings, Figure 1 is a longitudinal sectional elevation of a mixing and washing machine constructed in accordance with my invention. Fig. 2 is an end elevation of the same, partially in section, on the line 2 2 of Fig. 1. Fig. 3 is a plan view of the machine.

Similar numerals of reference are employed to indicate corresponding parts throughout the several figures of the drawings.

10 designates an open-top trough having a semicircular bottom portion and provided at

its opposite end with bearing-blocks 11 for the support of a longitudinally-disposed hollow shaft 12, on which is bolted a helical feed-screw 12', preferably formed of sheet metal and having inner flanges 13, by which it may be bolted to the shaft. The trough is supported on a transverse block 14, having carrying-wheels 15, which are disposed at a point 55 near one end of the machine, where the greatest weight is, and near the opposite end of said trough are two bracing-legs 16, which extend from side sills 17 to the ground, these legs being strengthened by diagonal brace-bars 18, as shown in Fig. 1. The legs 16 are placed at a sufficient distance from the end of the trough to permit a wheelbarrow or other receptacle to be placed under the discharge-opening 20 in the bottom of the trough without inconvenience, and thus render it unnecessary to shovel the material from the ground to the wheelbarrows. As a convenient means of moving the machine from place to place I employ a U-shaped handle 21, adapted to 70 socket-pieces 22 on the side sills, so that the handle may be moved in until the cross-bar 75 is close to the end of the trough and out of the way of the workmen.

At the front end of the machine is a feed-hopper 25, arranged immediately above the trough and having outwardly-flaring sides to permit the gravel or broken rock to be shoveled into the machine from one or both sides, as may be required.

At the top of the trough are outwardly-projecting flanges 26, through one of which is formed an opening for the passage of the mast of a crane-arm 27, the foot of the mast being stepped in a socket 28, carried by one of the 90 side sills, so that it may be freely revolved or removed when required.

The crane-arm serves to support a cement-receptacle 30, in the form of a cylindrical casing having a supporting-bail 31, the latter 95 being connected by a block and pawl to the crane-arm, so that the receptacle may be lowered to the ground when the supply of cement is to be replenished. In the upper portion of the receptacle is a screen 32, through which the cement is passed in order to break up any lumps and prevent the entrance of foreign material with the cement. The lower portion of the receptacle is contracted and ter-

minates in a discharge-orifice 33, which may be closed by a plug-valve 34, carried by a stem 35, which is connected to an external operating-arm 36, by which the valve may be 5 opened to any desired extent to permit the passage of a constant quantity of cement.

At a point below the discharge-mouth 33 is a flaring hood 38, preferably rectangular in form to correspond to the contour of the hopper 25. The hood extends partly within the mouth of the hopper, so as to prevent the blowing away of the cement by air-currents, and is held in place by hook-bars 39, extending from the edges of the hopper to the hood. 10 In the mouth of the hood is a curved screen 40, the highest portion of which is under the center of the discharge-mouth, so that the falling cement will be evenly distributed by the screen and the mixture with the material 15 in the trough rendered more uniform.

The hollow shaft 12 is provided with a balance-wheel 41, to which may be attached a crank 42 when the device is to be operated by manual power, or the wheel 41 may be 20 made to receive a driving-belt or may be in the form of a gear-wheel operated from any suitable source of power.

In some cases the cement will cake in the receptacle and the flow will be rendered uneven and irregular, especially during damp weather, and in order to render the discharge more certain and positive I employ a tappet-arm 43, pivoted in a bearing 44, projecting from the hopper, one end of the tappet-arm being provided with a block 45, of wood or similar material, for contact with the lower portion of the receptacle. The lower end of the tappet-arm is weighted and extends into the path of movement of one or more pins 35 carried by the balance-wheel.

In the operation of the device the receptacle is filled with cement, the capacity of the receptacle being such as to enable it to receive a quantity sufficient for a comparatively long 40 time. The plug-valve 34 is then opened to the desired extent and the material constituting the body of the concrete is shoveled or otherwise fed to the hopper. The shaft is continuously revolved and the feed-screw in 45 the trough thoroughly mixes the material and at the same time feeds it in the direction of the discharge-opening. Water is supplied during the mixing operation, so that the material discharged from the opening 20 into the wheelbarrows or other receptacles will be thoroughly-mixed concrete.

By the employment of a machine of this character I am enabled to obtain a continuous supply of concrete without the employment of a large force of laborers and at the same time prevent danger of the setting of one section of the pavement or other work in advance of the mixing of a fresh supply.

The machine may also be employed for the 60 washing of gravel or like material by forming openings at the front end of the trough, suitable discharge-pipes 48 extending from

said openings to sand-receptacles. When the device is used as a gravel-washer, the gravel is fed into the hopper and carried forward to the feed-screw to the discharge-opening, and at the same time a supply of water is directed by a hose or water pipe into the trough through the hopper 25, the water and sand flowing off through the pipes 48 to the 70 receptacles provided for the purpose, where the sand is retained and the water allowed to escape.

While the construction herein described, and illustrated in the accompanying drawings, is the preferred form of the device, it is obvious that various changes in the form, proportions, size, and minor details of the structure may be made without departing from the spirit or sacrificing any of the advantages of 85 the invention.

Having thus described the invention, what I claim is—

1. The combination with a trough having a hopper at one end and a discharge-opening at 90 the opposite end, of a conveying and mixing device arranged within the trough, a freely-movable cement-containing vessel loosely connected to the hopper, a supporting means to which said vessel is hung, said vessel having a discharge-opening immediately above the hopper, a screen carried by the vessel, a tappet member adapted to strike against the side of the vessel, and means for actuating 95 said tappet member. 100

2. The combination with a mixing-trough having a hopper at one end and a discharge-opening at the opposite end, of a conveying and mixing device arranged within the trough, a cement-receptacle disposed above 105 the hopper and having a discharge-opening, and an arched screen carried by the receptacle at a point below said discharge-opening.

3. The combination of a trough having a hopper and a discharge-opening, of a conveying 110 and mixing device disposed within the trough, a cement-receptacle having a bottom discharge-opening, a valve for closing said opening, a tappet member adapted to strike the receptacle to agitate the cement, means 115 for actuating the tappet, a supporting device carrying the receptacle and permitting free movement thereof, and means for raising and lowering said supporting device. 120

4. The combination with a trough having a hopper and a discharge-opening, a mixing device arranged within the trough, a removable containing vessel arranged above the hopper and having an open top and a lower contracted discharge-opening, a screen arranged 125 near the top of the vessel for preliminary screening of the material in advance of its entrance to said vessel, a second screen carried by the vessel at a point below the contracted discharge-opening, a valve adapted to 130 said opening, and a valve-operating means extending outside the vessel.

5. The combination with the trough having a hopper at one end and a discharge-opening

at the opposite end, of a hollow shaft extending longitudinally of the trough, a helical conveyer secured to and rotating with the shaft, means for turning the shaft, a containing vessel arranged above the hopper and having a bottom discharge-opening, a tappet for agitating the vessel, said tappet comprising an angular bar having an intermediate portion adapted to a bearing or support at the top of the hopper and provided with a horizontal arm for engaging the wall of the vessel, a weight forming a part of an approximately vertical depending portion of said arm, a wheel secured to the shaft, and tappet-pins carried by said wheel and adapted to operate the tappet.

6. The combination with a hopper, of a containing vessel mounted thereabove and having a lower discharge-opening, an arched screening device carried by said vessel at a

point below the discharge-opening, means for loosely connecting the vessel to the hopper, and means for agitating said vessel, substantially as specified.

7. The combination with a mixing-trough 25 having a wheeled support, of the side sills, handle-bars adjustable longitudinally of the sills, auxiliary supporting-legs depending from said sills, a mixing device within the trough, means for operating the same, and auxiliary discharge-openings arranged at the feed end of said trough, substantially as specified.

In testimony that I claim the foregoing as my own I have hereto affixed my signature in 35 the presence of two witnesses.

THOMAS HASKINS.
